[57] CLAIM

The ornamental design for a toothbrush, as shown and described.

DESCRIPTION

FIG. 1 is a perspective view of a first embodiment showing the handle portion of our new toothbrush design;

FIG. 2 is a top plan view thereof;

FIG. 3 is a right side elevational view thereof, the left side elevation being a mirror image thereof;

FIG. 4 is a bottom plan view thereof;

FIG. 5 is a front elevational view thereof;

FIG. 6 is a rear elevational view thereof;

FIG. 7 is a perspective view of a second embodiment of the handle portion of our new toothbrush design;

FIG. 8 is a top plan view thereof;

FIG. 9 is a right side elevational view thereof, the left side elevation being a mirror image thereof;

FIG. 10 is a bottom plan view thereof;

FIG. 11 is a front elevational view thereof;

FIG. 12 is a rear elevational view thereof;

FIG. 13 is a perspective view of a third embodiment showing our new toothbrush design;

FIG. 14 is a top plan view thereof;

FIG. 15 is a right side elevational view thereof, the left side elevation being a mirror image thereof;

FIG. 16 is a bottom plan view thereof;

FIG. 17 is a front elevational view thereof; and,

FIG. 18 is a rear elevational view thereof.
